A. TAUTGES.
DOOR STRUCTURE FOR GRAIN CARS AND THE LIKE.
APPLICATION FILED JUNE 24, 1916.

1,219,506.

Patented Mar. 20, 1917.

UNITED STATES PATENT OFFICE.

AUGUST TAUTGES, OF ANIWA, WISCONSIN, ASSIGNOR OF ONE-FIFTH TO JOE LINDNER, SR., AND ONE-FIFTH TO JOE LINDNER, JR., BOTH OF BIRNAMWOOD, WISCONSIN.

DOOR STRUCTURE FOR GRAIN-CARS AND THE LIKE.

1,219,506.

Specification of Letters Patent. Patented Mar. 20, 1917.

Application filed June 24, 1916. Serial No. 105,534.

To all whom it may concern:

Be it known that I, AUGUST TAUTGES, a citizen of the United States, and resident of Aniwa, in the county of Shawano and State 5 of Wisconsin, have invented certain new and useful Improvements in Door Structures for Grain-Cars and the like; and I do hereby declare that the following is a full, clear, and exact description thereof.

10 The present invention relates to new and useful improvements in doors, and is more particularly directed to the provision of an improved sliding door structure for association with freight cars adapted to contain 15 grain or other substances necessitating the provision of a tight engagement of the door structure to prevent leakage.

It is in general the object of the present invention to simplify the structure and improve 20 the efficiency and convenience of operation of door structures of this character, and it is more particularly an object to provide such a door structure comprising upper and lower independently operable sections.

It is further an object to provide an improved lever means for operating the door sections, whereby they may be held in engaging 25 relation with the frame or may be held spaced outwardly from the frame to permit their being slid to an open position.

With the above and other objects and advantages in view, the invention resides more particularly in the novel combination arrangement and formation of parts more particularly hereinafter described and pointed out in the appended claims.

In the drawings:

Figure 1 is an elevational view of a door structure embodying the present invention and with the upper door section slid away from the door opening.

Fig. 2 is a vertical sectional view through the side of the car at the door opening with both of the door sections swung away from the opening.

Referring now more particularly to the accompanying drawings 5 designates the side of a car which is provided with the 50 door opening 6, having the door seating flanges 7 at its inner side edges. Disposed above and below the door opening and extended to one side thereof are track bars 8 on which are mounted wheels 9 carried by 55 brackets 10 connected with the outer ends of

upper and lower door carrying frames 11 and 12 respectively, the track bars being provided with longitudinal grooves 13 slidably receiving finger portions 14 of the brackets whereby the brackets are held 60 against lateral movement with respect to the car side. The inner ends of the frames are slidably held by inwardly extending brackets 16 at the inner corners thereof, and these brackets carry at their free ends oppositely 65 projected rollers 16^a which are engageable in channel tracks formed by horizontal grooves 17 in the side of the car at one side of the door opening and plates 18 at the side edges of said groove extended inwardly 70 thereof to hold the rollers. At the opposite side of the door openings, the side of the car is provided with holding channel sections 19 to hold the respective bracket rollers 16 when the door frames are slid to closing position. Carried by the frames are upper 75 and lower door sections 20 and 21 respectively and these door sections are each connected at its upper portion with its respective frame by a pair of levers 22 journaled 80 at the sides of the frame and carrying pintles 23 journally secured to the side of the door section and extending laterally therewith. The lower end of each section is journally secured to corresponding pintles 24 carried 85 by links 25 pivoted to the lower side portions of the frame and these pintles 24 also extend laterally of the door sections.

Thus the door sections may either lie 90 within the door opening to provide a tight closure therefor, or may swing upwardly and away from the door opening, whereby their frames may be slid laterally of the door opening, to clear the same, the upper edge of the upper door section 20 being bevelled to correspond with a similar bevel of the upper edge of the door opening, whereby the upper door section may be readily swung to desired positions. The door sections are firmly held in closing position by 95 bracket plates 26 at the sides of the door openings which are engageable by the extended ends of the pintles 23 and 24.

For swinging the door sections a pair of levers 27 are intermediately pivoted to the 105 lower bar of each door frame and have their adjacent ends pivoted together and their outer ends connected by links 28 with the levers 22. Thus upon rocking one of each pair of levers 27 a respective door sec- 110

tion will be swung either to seating or unseating relation with the door opening and to provide a ready means for locking this lever and for holding the door frame in either desired limit of swinging movement, a combined handle and hasp bar 29 is hingedly connected to the lever adjacent its pivot on the frame and this bar is apertured to engage over either of a pair of horizontally spaced staples 30 on the lower sill of the frame. A pin 31 is loosely secured to the frame to lock the bar on either staple and if desired a suitable seal of conventional nature could be employed in connection with the hasp bar and staple.

I claim:

1. The combination with a wall having a door opening, a door carrying frame slidably mounted adjacent the door opening, a door, levers pivoted to the door and to the frame whereby the door may swing into and out of seating relation with the door opening, levers intermediately pivoted to the frame and having their ends pivotally connected, links connecting said second named

levers and the door levers, a pair of spaced holding members on the frame, and a handle pivotally connected with one of the second named levers and apertured to selectively engage the holding members. 30

2. The combination with a wall having a door opening of a door carrying frame slidably mounted adjacent the door opening, a door, links pivoted to the frame, lateral pintles carried by said links and journaled at the sides of the door whereby the door is held to swing into and out of seating relation with the door openings, said pintles projecting outwardly of the door and bracket members at the sides of the door 40 opening adapted to receive said pintles.

In testimony that I claim the foregoing I have hereunto set my hand at Aniwa, in the county of Shawano and State of Wisconsin, in the presence of two witnesses.

AUGUST TAUTGES.

Witnesses:
